LOCKER

Fredrick L. Brunswick, Oswego, N. Y.

Application December 3, 1934, Serial No. 755,820

7 Claims. (Cl. 312—174)

My invention relates to lockers, and more particularly to lockers for receiving apparel and locking it against removal and providing against tampering by unauthorized persons and for receiving and locking head wear against removal from the locker; and the nature and objects of the invention will be readily recognized and understood by those skilled in the arts to which it relates in the light of the following explanation and detailed description of the accompanying drawings illustrating what I at present believe to be the preferred embodiment or mechanical expressions of my invention from among various other forms, arrangements, combinations and constructions, of which the invention is capable within the spirit and scope thereof.

In schools, gymnasiums, shops and the like where it is generally common practice to remove all or a part of one's garments it is essential that some means be provided for safe-guarding the apparel which has been removed. Locking means such as are now in use which merely insure against theft of the garments themselves have been found unsatisfactory for such devices do not guard against and protect contents of the garment's pockets. Furthermore, the common closed locker while protecting the contents of the clothes is bulky and where large numbers of the lockers are required a large amount of floor space is necessary.

In an effort to overcome such faults and with further purposes in view it is among the objects of my invention to provide a locker to protect objects deposited therein from theft and tampering by unauthorized persons.

A further object of my invention is to provide a locker which is compact and of light but durable construction.

A still further object of this invention is to provide a locker of durable construction which requires a minimum of floor space.

Another object of my invention is the provision of a locker of relatively small proportions which will protect apparel and headwear without damaging or misshaping either.

It is also a feature of my invention to provide lockers of durable qualities which may be mounted in batteries upon walls and the like.

A further and more particular object of my invention is to provide a locker which is entirely and easily accessible when in opened or unlocked position.

A further characteristic of my invention is to provide a locker, the key of which is removable therefrom only when the locker is locked and in use.

It is also an object of my invention to provide a locker having space thereon to receive advertising or other reading matter.

My invention also includes as a feature thereof, a locker having headwear and apparel locking means which operate simultaneously.

A further object of my invention is to provide a locker which is operated to opened and closed position, by a simple and durable operating mechanism.

With the foregoing general objects, features and results in view, as well as certain others which will be apparent from the following explanation, the invention consists in certain novel features in design, construction, mounting and combination of elements, as will be more fully and particularly referred to and specified hereinafter.

Referring to the accompanying drawings:

Fig. 1 of the drawings is a view in elevation of a battery of lockers.

Fig. 2 of the drawings is a top plan view of the locker with certain parts thereof broken away.

Fig. 3 of the drawings is a view in vertical section through the locker taken on a line corresponding to 3—3 of Fig. 2.

Fig. 4 of the drawings is a side view of the locker in elevation with certain parts thereof broken away and with the locker in open position.

Fig. 5 of the drawings is a side view of the locker in closed and locked position.

Referring to the drawings, a locker unit 1 is disclosed having a closed cabinet portion 2 and a headwear supporting and locking portion 4 thereabove. The closed cabinet portion 2 of the locker 1 has a back 3, side walls 5, bottom 7 and 35 a top 9. Hinged to the side walls 5 are double doors 11 which swing outwardly to open, and when fully opened are in position parallel to the side walls 5 as may be clearly seen by referring to Fig. 2 of the drawings. The interior of the cabinet 2 of my locker is therefore entirely accessible when the doors 11 are swung to open position and when they are closed any objects deposited therein are kept concealed and inaccessible to the public or to dust and other deleterious matter.

As has hereinbefore been pointed out, this invention has been particularly designed for use as an apparel and headwear locker unit but it is not my desire to so limit the invention, as it is with 50 in the scope thereof to employ such a locker for the safekeeping and protecting of various types of goods and objects.

I have shown a coat hanger 13 and hook 15 mounted on the interior of cabinet 2 to the back 55

3 thereof. Although only one of these is shown in the drawings, it is to be understood that a plurality of hooks and hangers may be disposed within the cabinet on both the back surface 3 or the side walls 4 or they may be mounted and carried on the inner side of the doors 11. It is also intended that shelving or the like as in common use may be secured within the cabinet 2.

The headwear supporting and locking portion 4 comprises a flat headwear supporting and retaining member 17 vertically carried on the top of cabinet 2 and rigidly secured and fastened to the side walls 5 thereof by means of angle irons 19 which are riveted to the inner side of walls 3. The headwear supporting member 17 is substantially circular in shape to conform to the general outline of a hat, and is formed with a base portion 21 extending the width of the cabinet 2.

20 The member 17 is mounted to extend vertically upwardly from cabinet 2 at a point adjacent the center of the depth thereof but spaced forwardly therefrom, for a purpose to be pointed out hereinafter.

25 The base 21 of headwear supporting member 19 is slotted to provide two parallel vertical slots 18 which are disclosed particularly in Fig. 3 and Fig. 4 of the drawings, and the purpose of the slots will be later explained.

30 Carried within the cabinet 2 and consuming a small amount of space at the top of the cabinet are mounted the various elements operable to close the doors 11 and to lock headwear against the supporting member 17.

35 The outwardly swinging hinged doors 11 are operable simultaneously with the headwear locking means to close and open the cabinet and to lock and release a hat. For this purpose I have secured a bearing bracket 25 to the back wall 3 of the cabinet having two spaced bearing members 26 and 27 extending forwardly therefrom. A shaft 23 is journaled in the bearing members 26 and 27 and extends in one direction to pass through one of the side walls 5 as at 28 in Fig. 2 of the drawings.

40 I desire to point out at this time for further and later explanation that bearing bracket 25 is provided with a further member 29 positioned midway of and below the two bearing members 26 and 27 to extend forwardly a distance beyond the members 26 and 27. It is also to be noted that member 29 has a cut-out section 31 on the upper side thereof as will be later explained.

45 Shaft 23 where it passes through one of the side walls 5 is journaled in a bearing member 30 of any known and suitable type which is secured to wall 5 and the shaft 23 terminates in a stub end 32 beyond the bearing member 30.

An operating lever 34 is secured to the stub 32 of shaft 23 by means of a set screw 35, the lever 34 being provided with a handle portion 36. Referring particularly to Fig. 2 of the drawings, it will be understood that operating lever 34 is spaced sufficiently beyond cabinet 2 that the operator may grasp handle 36 thereof without striking cabinet 2 with his hand.

50 A worm gear 38 is secured on shaft 23 for rotating therewith by means of a collar 39 and set screw 41. The gear 38 is secured on shaft 23 at a point therealong equidistant from each of the bearing members 26 and 27 for revolving with shaft 23 when it is actuated by the operating lever 34. It is to be here noted that member 29 on its upper side is provided with a cut out section 31 of a shape to receive gear 38 therein.

5 Member 29, as has been stated, extends outwardly midway between bearing members 26 and 27 to a point beyond the ends of the bearing members where it carries a vertical shaft housing or sleeve 40 in which is journaled a shaft 42 at right angles to shaft 23. Shaft 42 is of greater length than the length of the housing 40 in which the shaft is adapted to revolve and is actuated by means of a gear 44 which is secured to the shaft in horizontal position by any common means such as a collar 46 and set screw 47 at a point adjacent the upper end of the shaft where it extends beyond the housing 40.

10 Gear 44 in position secured to shaft 42 is in mesh with gear 38 and is actuated thereby to revolve vertical shaft 42.

15 A circular disk 48 having a collar 50 integral therewith and adapted to receive therein the lower end of shaft 42 which extends beyond the housing 40 and to be secured thereto by screw 52 for revolving with shaft 42 is provided with a flat lower or under surface having diametrically opposed downwardly depending lugs 54 and 56 thereon.

20 Pivots mounted on the interior of cabinet 25 back 3 are two bell cranks 58 and 60, one being pivotally mounted on either side of disk 48 in the same plane as lugs 54 and 56.

25 By means of a link arrangement about to be described the bellcranks are operatively connected to disk 48 by the lugs 54 and 56 and to the swinging cabinet doors 11, the adjacent bellcrank and door being connected, whereby the door will be swung open and shut.

30 A link 62 connects one arm of bellcrank 58 with lug 54 and on the opposite side of cabinet 2 a link 62a connects one arm of bellcrank 60 with lug 56. Both of these links being pivotally secured to both the bellcranks and the lugs on the underside of disk 48.

35 Furthermore, referring particularly to Fig. 2 of the drawings it is to be understood that each link from the bellcrank to the disk is in operative pivotal connection with the outer arm of each bellcrank.

40 Additional links 64 and 64a connect the inner arms of the bellcrank 58 and 60 with the doors to which they are pivotally connected by any suitable means such as the brackets and pins 66.

45 Thus upon rotating shaft 23 the disk 48 is revolved sufficiently to swing the bellcranks 58 and 60 and open or close the doors through the action of the link mechanism which has just been described.

50 Mounted on the wall 3 of cabinet 2 on the side thereof through which shaft 23 extends is a locking mechanism 68 in the form of a closed box having a key hole 69 therein for receiving a releasing or unlocking key. A trip 70 extends from the forward side of box 68 and is adapted to snap over and catch a dog 72 provided for that purpose on the operating lever 34. Thus, when lever 34 is actuated to close doors 11, it is in vertical position as shown in Fig. 5 of the drawings and the dog 72 contacts trip 70 which snaps over the dog to hold the lever 34 in this vertical position closing and locking the cabinet. With the operating lever in vertical position closing the cabinet and locked by the trip, it is necessary to insert a key in keyhole 69 to actuate the locking mechanism in box 68 to release the dog 72 on the lever to allow the lever 34 to be rotated to horizontal position opening the cabinet 2.

55 As I have hereinbefore stated, a headwear securing and locking means is provided which 75

operates simultaneously with the opening and closing of the cabinet doors, to lock and unlock an article of headwear on the locker.

As this operating mechanism I employ two rocker arms 74 and 74a secured to shaft 23 on the inner side of and adjacent to bearing members 26 and 27. The rocker arms 74 and 74a are slightly curved at their outer ends to form an arcuate portion 75 which is slotted longitudinally 10 forming a slot 76 therein.

When the operating lever 34 is raised to horizontal position rocker arms 74 and 74a will be in vertical upwardly extending position and upon swinging lever 34 downwardly to vertical locked 15 position the shaft 23 will rotate rocking arms 74 and 74a forwardly to substantially a horizontal position with the arcuate portions 74 forward of shaft 23 and curved downwardly.

On the forward surface of housing 40 I secure 20 by any suitable means a support or bracket member 78 extending forwardly from the housing and bent at right angles to extend upwardly to form two arms 78a and 78b terminating at their uppermost ends in spaced bearing members 79 and 80.

25 A supporting and locking ring member 82 formed preferably of a flexible metal band is provided, the ring portion thereof being sufficient in size to receive therein a hat 82a, the brim 82b of which will rest on the ring member 82.

30 As is to be understood from the drawings, the hat supporting member 82 is shaped to substantially conform to the shape of a hat and the ends of the band forming the ring member 82 are not brought together but are bent from the member 35 to form two substantially parallel strips 83 and 83a slightly offset from member 82 as at 84.

Opposite downwardly depending lugs 85 are secured to strips 83 and 83a and are adapted for 40 pivotal mounting on bearing members 79 and 80, whereby the hat supporting member 82 and the parallel strips 83 and 83a are pivotally mounted and carried by the aforesaid bearing members.

The parallel strips are strengthened by means 45 of cross bars 86 and 86a which are secured to the strips 83 and 83a.

The inner or rear ends of strips 83 and 83a are provided with laterally extending pins 87 to slidably fit into slots 76 of the arcuate portions 75 of rocker arms 74 and 74a, suitable means being 50 provided for locking the pins into the slots, whereby upon rocking movement being imparted to the rocker arms 74 and 74a, the strips 83 and 83a will slide in slots 76 and that portion of the strips on the inner side of bearing members 79 and 80 will move downwardly or upwardly pivoting 55 on bearing members 79 and 80 whereby the hat supporting member 82 will either swing upwardly against supporting member 17 or downwardly therefrom to horizontal position for releasing a hat therefrom.

I shall now describe the operation and action of my invention which occurs when a person desiring to make use of it finds it in open unlocked position as disclosed in Fig. 2, Fig. 3 and Fig. 4 of the drawings.

The objects which are desired to be safeguarded being placed within the cabinet 2 and the hat being placed within the ring 82 which in open unlocked position is in outwardly extending horizontal position above the doors 11, the hat being so placed that the top side of the brim rests against the hat supporting member 82, the handle 36 of the operating lever 34 is grasped and the lever pressed downwardly until in vertical position with the dog 72 caught by the trip

70 of the locking mechanism contained within box 68. It is to be understood that the key being in keyhole 69 is not removable until lever 34 is locked by trip 70 and it is to be further understood that operating lever 34 is not movable when in locked position until the key is inserted in the keyhole to release the trip 70. With the unit locked, the position of the various parts and elements thereof are as disclosed in Figs. 1 and 5 of the drawings.

When the operating lever 34 is downwardly swung from open unlocked position to closed locked position, the shaft 23 is rotated and through the action of gears 38 and 44 and vertical shaft 42 the disk 48 is revolved in anti-clockwise direction to close doors 11 through the action of the links and bellcranks. The position of these various parts when the doors 11 are open is shown in full lines in Fig. 2 of the drawings and in closed position in the dotted lines in 20 the same figure of the drawings.

Now, when it is desired to open and unlock the unit from the position of Fig. 5 to that of full lines Fig. 2, the key is inserted in the locking mechanism and lever 34 is released for moving 25 to open horizontal position which through the means described revolves disk 48 in clockwise direction, the links 62 and 62a swinging the bellcranks to full line position, Fig. 2, and links 64 and 64a being moved by the bellcranks to open doors 20 11.

Simultaneously with the action closing the doors, the hat retaining ring 82 is swung upwardly against the hat supporting and locking member 17 as disclosed in Fig. 5 of the drawings to 35 hold a hat in locked position, the hat brim being locked between the ring 82 and member 17.

The member 17 is mounted on the top of cabinet 2 so that the brim of the hat will be pressed thereagainst by ring 82 when it is in vertical 40 or locking position as shown in Fig. 5 of the drawings.

When the shaft 23 is rotated by the downward movement of lever 34 the rocker arms 74 and 74a are rocked downwardly, whereupon the strips 83 and 83a slide in slots 76 and are carried downwardly by rocker arms 74 and 74a whereupon ring 82 is swung upwardly on pivots 79 and 80.

Upon swinging lever 34 to horizontal position opening the cabinet doors the hat ring 82 is simultaneously lowered to horizontal position through the rocker arms being upwardly swung causing the pivoting action of the ring and strips whereby the hat may be removed therefrom.

From the detailed description of my invention it 55 may be seen that it has been designed primarily for the safeguarding of apparel and headwear but is within the contemplation of this invention that it is capable of a variety of uses wherever it is necessary to safeguard belongings.

What I claim is:

1. In a locker unit a cabinet having doors mounted thereon, a headwear supporting and locking member, a manually operable member, means operably coupled with said manually operable member and with the doors, including a shaft and a link mechanism actuated thereby, whereby said doors are actuated to opened and closed position upon actuation of said manually operable member, and said headwear supporting 65 and locking member being operably associated with said manually operable member and actuated thereby to lock and unlock the headwear supporting and locking member simultaneously with the opening and closing of the doors.

2. A locker unit including a cabinet and a headwear supporting and locking means disposed thereabove, doors mounted on said cabinet to swing outwardly to cabinet open position and the interior of said cabinet being entirely accessible when the doors are in outwardly swung cabinet open position and the doors when in closed position forming the front of said cabinet, a manually operable member mounted in said cabinet, a link mechanism actuated thereby and operably coupled with said doors for opening and closing thereof, and means actuated by said manually operable member and operable simultaneously with the operation of the doors to actuate said headwear supporting and locking member to locked and unlocked position.

3. A locker unit for apparel and headwear and the like including a cabinet having doors mounted thereon, and a headwear supporting and locking member, and means for operating said doors to open and close the cabinet, including a manually operable shaft, a second shaft actuated by said first mentioned shaft, said second shaft carrying a member for actuation thereby and said second shaft carried member operatively associated with said doors to open and close the cabinet and means operated by actuation of said first shaft to actuate said headwear supporting and locking member to locked and unlocked position.

4. A locker unit for apparel and headwear and the like, including a cabinet having doors mounted thereon for horizontal swinging on a vertical axis forming in closed position the front of the cabinet, a headwear supporting and locking means mounted on said cabinet to extend thereabove, mechanism mounted within said cabinet and adjacent said headwear supporting and locking means for opening and closing said doors and operating said headwear supporting and locking means, including a horizontally disposed manually operable member, having an operating element on the exterior of the cabinet, means coupled with said manually operable member and the doors and the headwear supporting and locking means to open and close the doors simultaneously with locking and releasing the headwear supporting and locking means upon actuation of said manually operable member.

5. A locker unit, including a cabinet having doors mounted thereon for horizontal swinging on a vertical axis to cabinet opened and closed posi-

tion, a headwear supporting and locking member mounted above said cabinet, mechanism disposed within the cabinet in the area thereof adjacent said headwear supporting and locking member for operating the doors and the headwear supporting and locking member including a horizontally disposed manually operable member having a gear thereon and rotatable therewith and a rocker arm carried thereon for rocking movement upon actuation of the manually operable member, and means operatively associated with said gear and the doors to open and close said doors and said headwear supporting and locking member coupled with said rocker arm to operate said headwear supporting and locking means upon actuation of the manually operable member.

6. A locker unit, including a cabinet having doors mounted thereon for horizontal swinging about a vertical axis to cabinet opened and cabinet closed position, and a headwear supporting and locking member mounted above said cabinet, common manually operable means for actuating mechanism to simultaneously operate said doors and said headwear supporting and locking mechanism, said mechanism including a member operatively associated with and actuated by said common means, a link mechanism coupled with said member and the doors for swinging thereof to cabinet open and cabinet closed position upon actuation of said common means, and a member carried on said common means and coupled with said headwear supporting and locking member to operate the latter upon actuation of the common means.

7. A locker unit for apparel and headwear and the like, including a cabinet having doors mounted thereon and a headwear supporting and locking member, and common manually operable means for actuating mechanism to swing the doors to opened and closed position and to swing the headwear supporting and locking member to locked and unlocked position, said mechanism including a shaft, a member actuated thereby, a link mechanism operatively associated with said member and the doors, and mechanism operable simultaneously with the actuation of said link mechanism to swing said headwear supporting and locking member to headwear locking and unlocking position.

FREDRICK L. BRUNSWICK.
